UNITED STATES PATENT OFFICE.

ALBERT WILDEN, OF COLOGNE, GERMANY.

PLATEN PRINTING MACHINE.

Application filed July 6, 1922. Serial No. 573,166.

To all whom it may concern:

Be it known that I, ALBERT WILDEN, a German subject, residing at Cologne, Germany, have invented new and useful improvements in Platen Printing Machines, of which the following is a specification.

This invention relates to platen printing machines with vertically movable printing platen which is characterized by the simplicity of its construction and easy operation so that it can be used by unskilled persons.

In a previous machine invented by this applicant, the color printing was carried out by means of a ribbon; this, however, had the disadvantage that the print was not sharp; that in consequence of the various forms of ribbon in use and the uneven use of same smudges were produced, while at the same time the expensive color ribbons became quickly worn and the working expenses were too high.

Consequently, it was necessary to devise means for printing in colors without the use of ribbons by providing reciprocatory inking rollers adapted to convey the required colors from laterally disposed ink troughs. However, experience has proved that this leads to particular difficulties for the reason that the alternate forward and backward motion of the inking rollers had to be carried out quickly and in definite periods through the intervention of a comparatively slow rotary engine shaft which turns in the one direction only, while, further, there is but little space available for the mounting of the necessary gear.

The aforesaid objections are entirely avoided by the present invention. Moreover, the color mechanism is so arranged as to ensure an intensive and uniform application of colors.

The improved printing press is shown in the accompanying drawings by way of example and wherein:

Figure 1 is a longitudinal section of the printing press; Fig. 2 a sectional plan and Fig. 3 a cross section of same.

The printing platen 1 carrying the type receives alternate up and down motion through the intervention of eccentrics 3 on shaft 2. The platen is suitably guided by means of guide rods 4 depending from the platen and working in sleeves 5 of the bed-frame. The paper 6 for printing is drawn from a roller and passes horizontally along over a rubber plate 7 secured on a press

table 8 in such a manner that the down-moving type platen, previously inked, produces the impression. The intermittent advance of the paper from the roll is carried out by any suitable mechanism not shown here.

The inking of the type is carried out in the following manner:

In two rails 9, one at each side of the press, is carried the so-called inking carriage 10 provided with two inking rollers 11 and receiving an appropriate to and fro motion. On the left hand side of the press is an inking mechanism which imparts the ink to the inking rollers 11 previous to each impression. The inking mechanism will be herein-after described. The gear for reciprocating the inking carriage comprises a grooved cam 12 fixed on the main shaft of the press and engaging a pin 36 of a toothed-rack 13 in such a manner as to move said toothed-rack by a definite length forward and rearward during each complete revolution of the shaft. The toothed-rack 13 rotates a pinion 14 and thereby also imparts alternate rotation in opposite directions to two chain wheels 15 which, by means of a chain 16, cause the ink-carriage 10 to advance and retreat below the type for inking purposes.

The following is a description of the inking mechanism:

In the ink trough 17 is freely mounted a steel roller 18 furnished with the usual doctor 19 for regulating the film of ink. The ink trough with its roller is so mounted in the side walls of the inking mechanism as to have a slight horizontal play and it is ordinarily drawn outwards by a spring 20. Thus, only when a pin 21 on the tooth-wheel 22, before each impression, (or before each second impression), moves the ink trough slightly to the right, can the roller 18 contact for a short time with the gelatine roller 23, continuously driven by the shaft 2, and thereby ink the roller 23. The ink on roller 23 is then spread evenly by a roller 25 which is carried by a link 24 which swings on the shaft 26 of the roller 23.

The steel roller 25 receives, besides the continuous rotation, a gradual sidewise displacement. For this purpose, the roller 25 is mounted on its shaft by means of a feather and groove which allow endwise displacement. One end of the roller is cut so as to form an angular head 37, while a spring 27 at the opposite end presses the roller against a stationary pin 28, whereby

an endwise movement is imparted to the roller 25 at every revolution.

In their left-hand end position, the two horizontal inking rollers 11 of the ink carriage are retained by the oppositely disposed spring controlled steel rollers 25 and 27. The driven roller 23 now rotates the other rollers by friction so that the ink is well spread over the inking rollers 11.

- 10 The platen 1 of the press consists in a frame-like box, the bottom 29 of which is cut as at 30 in order to allow the type 31 to pass through in the downward direction, see Fig. 1, right-hand side. The type box is 15 furnished with adjacently placed type sticks 32 for holding the type 31. These type rest with a small projection upon the upper side of the sticks 32. These sticks are placed side by side in the type box so that the total 20 width can be arranged to suit any desired width of line. The sticks are hollow and composed of thin walls furnished at both ends with rectangular slides 33 which can be moved to and fro by means of upwardly 25 projecting pins 34, the two slides thus enabling the type set up in the sticks to be clamped therein at any suitable position. This is an advantage ensuring a quick and easy setting up of the type in each stick.
- 30 For securely retaining the slides in any position they are fitted at their underside with a flat spring 35 which presses and slides along the bottom of the stick.

I claim:

- 35 1. A flat printing press with color mecha-

nism and reciprocating ink-carriage, characterized in that the reciprocating movement of the ink carriage is obtained through the intervention of a uniformly rotating shaft which by its rotation actuates a reciprocating toothed-rack which latter actuates a chain and chain wheel drive adapted to induce at the required period, the to and fro movement of the ink-carriage, that is to say, the inking of the printing type.

2. Constructional form of the press according to claim 1, characterized in that the two adjacently mounted inking rollers of the ink carriage are retained, in the idle position of the ink carriage, between two vertically superposed spring controlled and continuously rotating rollers of the inking mechanism, whereby, on the one hand, the inking carriage is stopped in its idle position during the printing operation and on the other hand, ink is simultaneously applied during this period to the two inking rollers.

3. A constructional form of the press according to claims 1 and 2, characterized in that the necessary lateral distribution of the ink upon the inking rollers is effected by the axial movement of one or more ink carrying rollers owing to the fact that the upper and if desired also the lower of the two vertically superposed ink carrying rollers have their ends cut away at an angle and are spring pressed against a stationary pin.

ALBERT WILDEN.
